(57) **CLAIM**

The ornamental design for a hat brim, as shown and described.

DESCRIPTION

FIG. 1 is a top left perspective view of a hat brim in use; FIG. 2 is a bottom right perspective view of the hat brim; FIG. 3 is a front view thereof; FIG. 4 is a rear view thereof; FIG. 5 is a left side view thereof; FIG. 6 is a right side view thereof; FIG. 7 is a top view thereof; and, FIG. 8 is a bottom view thereof.

The broken-line outline of the partial human figure illustrates how the claimed design may appear when worn and forms no part of the claimed design. The portion of the hat rendered in broken lines depicts environmental structure that forms no part of the claimed design. The dot and dashed lines form a boundary to the claimed design and form no part thereof.
